UNITED STATES PATENT OFFICE.

ROBERT WORLEY RHODES, OF GREENSBURG, PENNSYLVANIA.

ROTARY MOTOR.

Application filed September 16, 1920. Serial No. 410,751.

To all whom it may concern:

Be it known that I, ROBERT WORLEY RHODES, a citizen of the United States, and a resident of Greensburg, in the county of 5 Westmoreland and State of Pennsylvania, have invented certain new and useful Improvements in Rotary Motors, of which the following is a specification.

This invention relates to rotary motors of 10 the class of those where the prime driving elements are actuated by the motive fluid pressure.

One of the objects has been to so design the 15 parts of a rotary engine or motor of this class that its parts shall be simple in construction and adapted to be compactly arranged and, as an entirety, light and readily portable.

My improved engine may be regarded as 20 having a cylinder and two prime rotary driven elements which initially respond to the action of the motive agent, and each of which is adapted to act as an abutment for the other while the latter is functioning as 25 a piston, both being concentrically rotatable in the same circular paths.

Each prime driving element includes a 30 driver or plurality of drivers against which is initially exerted the pressure of a motive agent. And these drivers of both elements are parts which travel in the same circular paths around the axis of the motor.

Preferably, the two driving elements are 35 so related to each other and to the other parts of the engine that they rotate intermittently, and alternately, in the same direction. There being more than one driver included in the driving element, they are arranged so that the drivers of the entire 40 engine can be regarded as being in two sets of pairs, the drivers of one set alternating, peripherally, with the drivers of the other set, and each driver being adapted to serve as an abutment, that is, receive the reactionary effort of the motive agent while the 45 drivers of the other set are advancing.

These drivers are preferably formed of 50 radially arranged blades or plates, those of the set included in one driving element alternating, as aforesaid, with the driving blades of the set included in the other element. In operation, each blade is brought to a position close to that of a blade in the other set and is immediately thereafter 55 positioned so as to be close to another blade of the second set.

The two prime driving elements, each including one or more drivers, are connected to a third, a driven, rotary element by suitable power transmitting devices which are 60 so constructed and arranged that a continuous rotary movement is imparted to the driven element.

In the drawings I have shown one of the numerous forms of mechanism which can be 65 constructed to embody my improvements. In order that the essential principles of it may be readily understood I will describe, somewhat in detail, the features of structure and mode of operation of the specific 70 parts which have been selected for illustration; it being understood, however, that in many respects there can be modification without departure from its essential features. 75

Fig. 1 is a bottom plan view of a rotary motor embodying my improvements.

Fig. 2 is an end view of the same.

Fig. 3 is a section taken along the plane 80 of the axis.

Fig. 4 is a section taken on a plane of the line 4, 4 of Fig. 3.

Fig. 5 is a section on a plane of the line 5, 5 of Fig. 3.

Fig. 6 is a transverse section on the line 85 6, 6 of Fig. 3.

Fig. 7 is a section on the line 7, 7 of Fig. 3.

Fig. 8 is a section on the line 8, 8 of 90 Fig. 3.

Fig. 9 is a section on the line 9, 9 of Fig. 3.

Fig. 10 is a section on the line 10, 10 of Fig. 3.

Fig. 11 is a section on the line 11, 11 of 95 Fig. 3.

Fig. 12 is a detail longitudinal section of the central shaft of the motor, and

Fig. 13 is a perspective view of one of the 100 valves and bushings.

As shown, there is an outer relatively stationary casing or shell-like part indicated as a whole by 40. In order to provide for the positioning and supporting of the parts to be described, this casing or shell is formed with the two main elements 41, 42, each so shaped that suitable chambers, ports and passages can be formed therein. At the end of the part 41 there is a transversely narrowed element 41^a of the casing, the metal 110 of which is disposed in such way as to provide for the forming of valve chambers to

control the inlet and exhaust of the motive agent.

The main driving elements are respectively indicated as entireties by 10 and 43. 5 The element 10 is a shaft-like device mounted at the center, axially, of the engine, and comprises a relatively elongated part 10^a with a cylindrical enlargement at 10^b. At one end the shaft is supported in the concentric tubular bearing 43^a, and at the other end its reduced extremity 10^c is fitted in the driven rotary element 44, as will be described.

The second main driving element 43 comprises the sleeve 43^a, the radially positioned plate 43^b, the opposed radial plate 47, the connecting peripheral ring 48, fastened by screws 49, and the short sleeve 46. The drivers of one set are secured to or formed 15 with the peripheral part 48, as will be described.

The driven rotary element 44 is mounted in a cap-like part 50 having the reduced central sleeve 51 and a radially extended plate 25 52, the latter formed with a threaded flange engaging with a thread at 53 at the end of the main casing 40. The reduced end 10^c of the central driving element 10 is journaled in a bearing recess at 54 in the driven element 44. To the second shouldered section 30 10^d of the part 10 is fitted a gear plate 55.

At the opposite end of the shaft a stop device in the form of a ratchet wheel 9 is secured on 10^a. The second or outer main driving element 43 is also provided with a ratchet wheel 12, secured to its tubular part 43^a. It will be seen that the two driving elements which have been described, namely, 35 the central shaft-like part 10 and the surrounding hollow part 43, can have rotary movement imparted to them independent of each other. And to so move them, I provide each with a set of the drivers above referred 40 to, so positioned that a motive agent can be caused to bear against their faces with resulting step by step movements of the driving elements as an entirety. 27, 27 indicate driving blades carried by the outer element 43; and 28, 28 indicate the driving blades carried by the driving element 10. The latter blades 28, 28 are shown as being integral with the enlarged part 10^b of the shaft. The metal at 10^b can, initially, be a large cylinder 50 and sections can be removed by machining until the central core part 10^b is formed and the integral radially extending driver blades 28.

The blades 27 are preferably made to have 60 the cross section shown, the outer or base part being somewhat flared, and the ring 48 having flared slots into which the bases of the blades can be tightly fitted. The width dimension of each blade 27 is such that its inner edge is fitted steamtight to the periph-

ery of the cylindrical part 10^b of the inner driving element. The blades 28 of the central element 10 alternate with the blades 27 peripherally; and their outer edges are positioned in steamtight relationship to the inner 70 concave surface of the ring 48.

It will be seen that if the driving blades 27, 28 of the two sets are relatively positioned as shown in Fig. 6, that is so positioned that they constitute a series of pairs, 75 the blades 27, and, with them, the other parts of the outer driving element can move clockwise until they respectively come to the blades 28; and also seen that, thereafter, the driving blades 28 (and the central main 80 driving element which carries them) can advance clockwise for a similar distance and in the same direction with a step movement. The pressure-receiving face of each driver blade is cut away, as shown at 27^a and 28^a, 85 to provide pressure-receiving chambers 28^b.

I cause the driving elements to thus move alternately, and advance step by step in the same direction by introducing at proper times a fluid motive agent and providing 90 suitable mechanism for letting it in and cutting it off, as will be described.

I lock against retrogression each of the prime driving elements after it has advanced a step. This is accomplished by the above mentioned ratchet wheels 9 and 12 and the companion pawls 8 and 13. The pawl 8 is normally positioned approximately in the horizontal transverse planes of the ratchet wheel 9. And the pawl 13 is similarly positioned in relation to the ratchet wheel 12. For these pawls, respectively, pockets or tubular chambers 8^a and 13^a are formed in the casing casting. They extend laterally in opposite directions. Each is 100 provided with a pivot as at 8^b, 13^b for supporting a pawl, and the chambers are closed by threaded caps 8^c, 13^c. Each ratchet wheel is provided with six teeth as at 9^d, 10^d, etc., for a purpose to be explained. 110

The inner and the outer driving rotary elements advancing step by step around the axis (clockwise when viewed as in Figs. 6 and 11) transmit continuous rotary motion to the driven element 44 by the following 115 devices. The gear wheel 55, above mentioned as being secured to the shouldered part 10^d of the inner rotary element 10 meshes with each of four segmental pinions, 56, 57, 58, 59. Each of these is loosely mounted on a shouldered stud shaft 60, and the four stud shafts are rigidly secured in a flange 61 formed with or secured to the rotary element 44. Each segmental pinion 56, 57, etc., is integral with a toothed wheel segment of longer radius than that of its pinion, the segments being respectively designated by 56^a, 57^a, 58^a, 59^a. The stud shafts 60 on which these segments 56^a, 57^a, etc., are mounted are so positioned relatively to the 120 125 130

main axis that the pitch circle of each segment is tangent to the pitch circle of a relatively large, internally toothed wheel 63. This wheel 63 is secured to or has its teeth formed integrally with a part of the outer driving element 48. As shown, the teeth are integral with a flange 62 cast with the radial plate 47.

When the internal wheel part 63 is advancing a step as part of the hollow element 48, it causes the gear segments to simultaneously rock on their axes and, at the same time, bodily advance a step around the main axis. And the advance of the shafts 59 causes a corresponding advance of the driven element 44. The larger segments 56^a, 57^a, etc., are turned into positions opposite to that shown in Fig. 11, during such a movement. At this time the central wheel 55 is locked by the dog 8 against backward rotation.

When the outer hollow part 48 has reached the end of a movement step, the parts are so related that the pressure agent causes the inner element 10 to advance a step, the outer element being now locked by the dog 13. While the central shaft 10 and its wheel 55 are advancing through this step movement they impart a partial rotation to each of the double segments, causing it to relatively rock again into the position shown in Fig. 11. The driven element 44 is thus maintained in continuous rotation by the alternating movements of the parts 10 and 48.

7 and 14 are piston-like valves respectively positioned in chambers 7^a and 14^a formed in the metal 41^a at the end of the casing 40. They are respectively fitted in bushing tubes 7^b and 14^b, which are tightly seated in said chamber. The piston valve 7 bears against the stop dog 8 and the valve 14 against the dog at 13.

The bushing tube 7^b has a series of grooves formed in its periphery, 7^c, 7^d, 7^e, 7^f, 7^g, 7^h. Apertures 7ⁱ extend through the metal of the tube from the bottom of each groove to its interior surface.

The valve 7 is formed with two grooves 7^c, 7^d, in its peripheral surface, of a width, axially, sufficient to have each groove register with the apertures 7ⁱ of two adjacent grooves such as at 7^e, 7^f, in the periphery of the bushing 7^b. The valve can be moved so that each of its grooves will at one time connect two of the peripheral grooves of the bushing, and at another time give a different registering connection of grooves.

The valve of the bushing tube 14^b is provided with similar peripheral grooves 14^c, 14^d, 14^e, 14^g, 14^h, 14ⁱ, extending from the groove to the interior surface of the bushing.

And the valve 14 is, like valve 7, formed with two wide peripheral grooves 14^c, 14^d.

Passages 90, 91, 92 and 93 to the atmosphere are formed in the wall of the casing 40

from four of the grooved portways in the valve bushings 7^b and 14^b, two of these portways being in each valve, to permit the exhaust of the air from the cylinder part 48.

The pawl or stop dog 8, at its end, has a lug 8^a projecting in such way as to be adapted to engage with the teeth 9^a, 9^b, etc., of the ratchet wheels 9; and also has a lug above it, indicated by 8^b, and which bears against the end of the piston valve 7.

The teeth 9^a, 9^b, etc., of the ratchet wheel 9 are formed so that their peripheral surfaces have a peculiar action in relation to the valve 7. The radial face or edge of each tooth is indicated by 9^c; the opposite edge of the tooth by 9^d, the crown part by 9^e, and the root space by 9^f. The crown part 9^e is elongated somewhat peripherally and adapted, when engaging with the dog or lug 8^a of pawl 8, to hold it up for an appreciable time. The root space 9^f is somewhat elongated and permits the wheel to move a few degrees before the pawl or dog is engaged by the curved space 9^g of the tooth, the lug 8^a on the dog, during this short period, riding on the crown part 9^e of the wheel.

The pawl 13 is formed to have its details correspond to those just described for the pawl 8, that is has a pawl lug 13^a and an outer lug 13^b. And the wheel 12 has its teeth formed each with an elongated crown face 12^c, a root space 12^d, a ratchet edge or face 12^e, and a curved face 12^f.

At 22 there is a passage with a threaded wall into which can be fitted a supply pipe 22^a for air, steam or equivalent. 19 is a duct extending from this passage to a port 1 above the upper piston valve 7. 21 is a port extending inward to admit pressure below the piston 14. 4 and 17 are ports through the walls of the valve chambers 7^a and 14^a.

63 and 64 are ducts extending from the valve chamber 7^a through the metal of the casing 40 to the periphery of the rotatable sleeve 43^a; and 65, 66 are similar ducts leading from the valve chamber 14^a to the periphery of the rotatable sleeve 43^a, but terminating at points nearer the inner end of the sleeve than do the ducts 63 and 64. 68, 69, 70 and 71 are annular grooves in the periphery of the rotatable sleeve 43^a. At one point in each of the grooves 68, 69, etc., an aperture is formed extending from the base of the groove through the metal of the sleeve 43^a, as shown at 72, 73, etc. These apertures are arranged to coincide with the radial apertures 76^a, 77^a, etc., respectively, in the central shaft or driving element 10, the latter apertures connecting with the longitudinal ducts 76 and 77 which are formed in this shaft.

The enlarged part 10^b of the rotary element is formed with ducts 78, 78 leading to the periphery thereof, which communicate with the longitudinal duct 76; and also with 130

ducts 80, 80 which communicate with the longitudinal duct 77. It will be understood, of course, that only one of each of the ducts 78, 78, is necessary to admit the air to the compression chambers between the driver blades 27 and 28, but to decrease the amount of resistance to the flow of the pressure agent through these connecting paths I have provided four apertures from the central longitudinal ducts 76 and 77 to each of the regions of intermittent compression between the driver blades.

The operation of the devices controlling the inlet and exhaust ports is as follows:

- 15 If it be assumed that the valves 7 and 14 and all of the ports and ducts are positioned as shown in Figs. 3 and 6, the pressure agent, when admitted through 22, will flow through the duct 19, and through port 4, 20 enter the valve chamber 7^a; it then passes through the portways 7^t, 7^s, which at this instant register with the annular groove 7^c, and flows through the duct 64 to the sleeve 43^a; it then enters duct 76 through the aperture 73. From duct 76 it flows through the apertures 78, 78, to the spaces 28^b, each between a blade 27 and a blade 28. The pressure advances the driving element 43 one-twelfth of a revolution. During this movement the air in front of the blades 28 is exhausted through the ducts 80, 80 and 77, apertures 72, 77^a, duct 63, portways 7^h, 7^t, and exhaust port 91, to the atmosphere.

- 35 The partial rotation of the driving element 43 causes a tooth of the ratchet 12 to lift dog 13, and this in turn moves outward valve 14. The latter moves to a point where the passage from port 17 to duct 65, and the sleeve 43^a is opened, and an exhaust passage from duct 66 to the atmosphere port 93 is opened. During this time the registering apertures 72, 73 and 76^a, 77^a move relatively to each other and the ducts 63 and 64 are closed. Then apertures 74 and 75 register with apertures 76^b and 77^b, and, the working air now coming through duct 65 passes through these apertures and the duct 76 to the working chamber, and the exhaust air passes out through ducts 77, 66, and from 50 the latter through bushing portways 14^t and 14^s, past valve 14 and through the port 93 to the atmosphere.

- 55 During this latter period of time the outer driving element 43 is advanced through another one-twelfth of a revolution, that is through the other half of a step. And this rotary movement carries the ratchet wheel 12 far enough to pass the crown part of a tooth under the lug 13^d, this crown holding the valve 14 in its outer position during the last described inlet and exhaust of air past it. The advance of the wheel 12 continues during this movement of air through ducts 65 and 66 until the point of a wheel tooth 65 passes under the point 13^d of the dog; where-

upon the pawl is instantly moved toward the axis, locks the wheel against retrogression, and permits the valve 14 to be moved far enough to reverse the connections of ports and ducts.

70 The air entering through the duct 17 now passes through the bushing ports 14^t, 14^s, groove 14^c, duct 66, apertures 75, 77^b, and duct 77 into the working chamber. The exhaust passes out through duct 76, apertures 76^b and 74, duct 65, ports 14^b, 14^t and 14^d, and exhaust port 92. At the instant of commencement of reversal of the air, just described, the blades 27 had completed their forward step, and had, respectively, reached the blades 28 in front of them. The air is admitted into the chambers between each blade 27, and the blade 28 immediately in front thereof, the former being held as abutments by the dog 13 and ratchet 12, and the blades 28 commence their cycle of revolution.

75 It will be seen that the valve 7 first controls the inlet and the outlet of an impulse of air, which causes one of the driving elements to move through the first half of a step, simultaneously causing a movement of the other valve 14, to where the latter can control an air impulse which moves the same element through the second half of a step or the second twelfth of a revolution. The second valve 14 controls the air which causes the second driving element to advance through the first half of a step of the second driving element.

80 During the first part of the step while blades 28 move forward and blades 27 are held stationary, the incoming and exhausting air continues to pass through the ducts 66 and 65 around the ports in the valve 14 and in the bushing 14^a. This continues until the driving element 10 has rotated to such a point that the registering apertures 77^b and 75 and 76^b and 74 have moved out of alignment and the passage of air there-through is cut off. Immediately afterward the apertures 72 and 77^a and apertures 73 and 76^a register with each other and the air is free to pass.

85 The valve 7 now becomes the controlling valve for the incoming and exhausting air, since the movement of the blades 28 causes the central driving element 10 to rotate and to actuate the valve 7 through the medium of the ratchet 9 and the dog 8. The operation of the valve 7 is identical with that of the valve 14. I have described above the latter part of the cycle of operation when the air is admitted through the port 4 and through the valve 7 into the duct 64 and through the several registering portways to the driving chamber. During the first part, however, of the cycle now being described, the valve 7 has been lifted by the dog 8 and the ratchet 9, and the incoming air passes 90

from the port 4 around the valve 7, through the groove 7^a and through the ports 7^g, 7^h, and thence into the duct 63; then through the ports 72, 77^a into the duct 77 and into the driving chamber through the ducts 80, 80, etc. The exhaust air passes through the ducts 78, 78, through the duct 76 and through the ports 76^a and 73 to the duct 64, then around the valve 7 through the bushing ports 7^e, 7^f, and the portway 7^c to the atmosphere through the duct 90.

After the driving element 10 has rotated through a predetermined part of a cycle the dog 8 passes over a tooth of the ratchet wheel 9 and falls into a root space between that tooth and the next succeeding, and the valve is forced into the position shown in Figs. 3 and 4. The positions of the valves and the several portways and ducts are now the same as those described at the beginning of the first step. At the ends of the movements just described the second driving element, with its blades 28, terminates the second half of its forward step, and as marked, the various parts are again in the positions shown in Figs. 3 and 6, and are ready for another pair of steps.

I claim:

1. A rotary engine, comprising a shaft with radial blades, a concentric driving element with opposing blades, revoluble on the shaft and forming a chamber holding means associated with the shaft preventing retrograde movement of the radial blades while the driving element moves forwardly a predetermined distance, and valve mechanism actuated by said holding means when the element reaches the end of said distance for introducing a charge of motive fluid between the opposing blades then in contiguity.

2. A rotary engine, comprising a shaft with radial blades and a ratchet, a concentric driving element defining a chamber, with opposing blades revolubly moving said element on the shaft through an incoming charge of fluid; a pawl engaging the ratchet holding the shaft and radial blades against retrogression, and valve mechanism associated with the driving element held open to admit the charge of fluid a predetermined time, including means then holding the driving element against retrogression while the shaft is moved forwardly.

3. A rotary engine, comprising a pair of alternately revoluble driving elements, each with blades in opposition, alternately acting as abutments and pistons; valve mechanism for introducing fluid between the blades when certain sets act as abutments and pistons respectively, at the same time enabling the exhaust of spent fluid in front of the ad-

vancing pistons; a second valve mechanism for introducing fluid between the advanced pistons and contiguous abutments, which latter then act as pistons, the former as abutments, and means associated with each valve mechanism for holding the blades of the then stationary driving element against retrogression.

4. The combination in a rotary engine, of a driving element with blades and a ratchet, a pawl engaging the ratchet to hold said element and blades against retrogression at predetermined times, and fluid valve mechanism associated with the pawl, including a ported valve member bearing thereon, to be shifted thereby through the ratchet when said blades move at other predetermined times.

5. The combination in a rotary engine, of a casing with fluid ports, a valve mechanism associated with each set of ports, a ported shaft with radial blades, a driving element rotatable on the shaft, having opposing blades, with certain ports continuously registering with the casing port and other intermittently registering with the shaft port; and means respectively carried by the shaft and driving element alternately holding the shaft and driving element against retrogression, and actuating the valve mechanisms to produce intermittent forward movement of the shaft and driving elements in alternation.

6. The combination in a rotary engine, of a casing with fluid ports, a valve mechanism associated with each set of ports, a ported shaft with radial blades, a driving element rotatable on the shaft, having opposing blades, with certain ports continuously registering with the casing port and other intermittently registering with the shaft port; means respectively carried by the shaft and driving element alternately holding the shaft and driving element against retrogression, and actuating the valve mechanisms to produce intermittent forward movement of the shaft and driving element in alternation, and means associated with the shaft and driving element for transforming said intermittent movements into continuous rotational movement.

7. A rotary engine, including intermittently and alternately revoluble driving elements, each with teeth; a driven spindle, and gear segments mounted on a part thereof and meshing with the respective teeth, to be rocked on their mountings in alternately opposite directions and ultimately to transform the intermittent movements of both driving elements into continuous rotation of the spindle.

ROBERT WORLEY RHODES.
